UNITED STATES PATENT OFFICE.

WILLIAM W. HARRIS, OF NEWPORT, NEW JERSEY.

SOAP STICK AND HOLDER.

Application filed April 13, 1921. Serial No. 460,991.

My invention relates particularly to soap sticks and holders for same, especially of the type in which the holder forms the body part of the soap stick container.

5 A principal object of the invention is to provide simple means whereby the stub end of a used soap stick is automatically positioned and retained on the usable end of a new stick when the latter is inserted in the 10 holder, thus effecting the economy of using the entire stub without any inconvenience whatever to the user.

Another object of the invention is to provide a holder of ample gripping proportions 15 and which also serves to form a considerable portion of the container thus reducing the expense of the container as a whole.

Another further object of the invention is to provide simple and sanitary clamping 20 means within the holder by which the soap stick is readily retained in any desired position and which is of such a nature as to be non-corrosive and otherwise innocuous to the soap stick, thereby rendering it unnecessary to protect each stick of soap with waxed 25 paper, tinfoil or the like. The doing away with the necessity of such wrappings is not only of great economic importance but also eliminates a source of much inconvenience 30 to the user, as wrappings of such nature become imbedded in the soap by continued pressure of the fingers or by the pressure of the retaining means such as used in other holders heretofore suggested in the art.

35 Further objects of the invention will be apparent from the following description and accompanying drawings in which

Fig. 1 is a side elevation partly broken away, of a full-length shaving stick and its 40 holder embodying my invention;

Fig. 2 is a detail perspective view of the clamping element shown in Fig. 1;

Fig. 3 is a longitudinal central sectional view of the holder proper and its cover and cap, but showing the soap stick used to the 45 limit of the holder proper;

Fig. 4 is a longitudinal central sectional view, of the holder proper and its cover, the soap stick being further reduced to a stub and a fresh full-length soap stick being 50 shown in an initial position of insertion; and

Fig. 5 is a longitudinal central sectional view, similar to Fig. 4, but showing the fresh 55 full-length soap stick fully inserted with the soap stub anchored thereon.

Referring to the drawings, the holder proper 1 is provided with the forward opening 2 through which projects the soap stick 3. The cover 4 is shown closed at its outer 60 end 5 and adapted to be frictionally or otherwise secured at its open end 6 about the forward end 2 of the holder proper 1.

The holder proper 1 is provided with the open rearward end 7 and is provided with 65 external threading meshing with corresponding internal threading of the cap 8.

Such forward end portion 2 of the holder proper 1 is forwardly inwardly tapered as of frusto-conical or like contour and coacting therewith is provided the split tube 9 of cardboard or like material which is innocuous to soap. Such cardboard 9 may be cut from flat stock and turned to form a slotted tube and is of such length that its forward 70 end is forced within the clearance between the tapered end 2 of the holder proper 1 and the soap stick 3 and abutting at its rearward end against the inner face of the flange of the cap 8, whereby upon tightening the 75 cap 8 the soap stick 3 is clamped at the forward end 2 of the holder proper 1.

Preferably the holder proper 1 is provided with the beading 10 to facilitate gripping manually of the holder proper and 80 which also serve as a stop for the edge of the open end of the cover 4.

The holder proper 1 may be beaded at 11 similarly to facilitate gripping of the same; the cover 4 may be provided at 12 with a 85 beading for ornamental or other purposes.

Preferably, the cover 4 is lined with the inner tube 13 of paper or the like and may be permanently positioned therewithin.

The soap stick 3 is shown of full length in 95 Fig. 1, namely approximately of a length extending from the inner face of the cap 8 to the inner face of the top 5 of the cover 4.

Such soap stick 3 is formed with the projection 14, preferably of tapering conical 100 contour and having the rounded outer edge 15 and the inner fillet portion 16. At its opposite end the soap stick is formed with the recess 17 of general cylindrical contour. The soap stick with its forward projection 105 14 and its rearward recess 17 are usually formed by molding the same in proper molds, as will be understood.

In Fig. 3 I have shown the soap stick 3 used up to approximately that limited by the 110 forward end portion 2 of the holder proper 1. In order to progress the unused portion

of the original soap stick 3 forwardly, the cap 8 is loosened to thereby permit the clamping tube 9 to be released manually or otherwise from frictional engagement with 5 the soap stick 3, and upon passing a finger through the open end of the cap 8 the soap stick is pushed forwardly until it abuts against the inner face of the top 5 of the cap 4, whereupon the cap 8 is now tightened to 10 move the clamping tube 9 again to its clamping position.

The soap stick is now prepared for further use and in Fig. 4 I have shown the same used down to the stub indicated at 16, comprising 15 substantially an annular ring of soap and the recess 17 of the original soap stick now extends through such stub 16. A fresh soap stick 3^a is now pushed through the open end of the cap 8, passed through the split tube 9 20 until the projection 14^a of the fresh soap stick 3^a is fully entered into the annular opening 17 to anchor the stub 16 onto the fresh soap stick 3^a, and the fresh soap 3^a is progressed still further forwardly of the 25 holder proper 1 carrying the stub 16 anchored on the projection 14^a, as is indicated in Fig. 5, whereupon the cap 8 is again tightened to move the clamping ring 9 to its clamping position.

30 The rounded forward portion 15 of a fresh soap stick facilitates entry of its projection within the annular opening of the stub of the previous soap stick. The fillet functions as a wedge with the rearward edge of the 35 annular stub in the operation of anchoring the stub on the fresh soap stick.

As will be noted, the cardboard clamping element serves to obviate the need of wax paper, metal foil, or other wrapping for the 40 soap stick as is required in shaving stick holders heretofore proposed. The clamping member in the form of a split ring serves also to adjust itself automatically to varying diameters or other irregularities of soap 45 sticks, incident to molding. The cap 8 may be of the closed end type if desired, in which case the cap is manually removed from the rearward end of the holder proper 1 when progressing forwardly the unused 50 portion of a soap stick and when inserting a fresh soap stick within the holder.

My invention is advantageous in avoiding loss of soap in that the clamping is effected by pressure alone and directly against the

soap stick without any intermediate wax 65 paper, or foil or the like.

The invention is also advantageous in that the clamping ring or other clamping element is disposed solely within the holder proper and carried wholly by the holder proper. 60 When the shaving stick holder is entirely disassembled there are but three loose parts which are readily replaced in their respective assembled positions.

Whereas, I have described my invention 65 by reference to specific forms thereof it will be understood that many changes and modifications may be made without departing from the spirit of the invention.

I claim:

1. A soap stick holder comprising a tubular holder of metallic material and provided with a contracted forward open end and a movable strip of cardboard serving as a wedging element in coaction with said contracted forward end, said strip of cardboard being freely folded about a circular stick of soap and disposed about substantially the whole of the inner face of the holder and for all its positions retained within the holder to engage the inner surface of said tubular holder and including the inner surface of said contracted forward end, said tubular holder having an open rearward end to afford access manually to the rearward end of 85 the stick of soap.

2. A soap stick holder comprising a tubular holder of metallic material and provided with a conically contracted forward open end and a movable strip of cardboard serving as a wedging element in coaction with said conically contracted forward end, said strip of cardboard being freely disposed within said tubular holder and for all of its positions wholly within said tubular holder, said strip of cardboard being folded to surround a circular stick of soap when disposed within said tubular holder and to wholly engage the inner surface of said tubular holder and including the inner surface of said conically contracted forward end, said tubular holder having an open rearward end to afford access manually to the rearward end of 100 the stick of soap.

In testimony whereof I have signed this 105 specification this 8th day of April, 1921.

WILLIAM W. HARRIS.
